NEBRASKA

WRENCH

Application filed March 20, 1931. Serial No. 524,130.

Our present invention has reference to a ratchet nut wrench and among the objects in view is to provide a simple, cheaply constructed wrench for this purpose which is designed for general use and in which the ratchet wheel connected with the socket of the wrench is engaged by one of two ends of a dog, and the pivot for the dog being provided with a swingable handle to which is attached a spring, whereby either of the active ends of the dog may be brought to engage with the ratchet wheel so that a nut or the like received in the socket of the wrench or in a socket member attached to the wrench may be easily and quickly screwed home or unscrewed without necessitating the removal of the wrench from the nut or bolt.

To the attainment of the foregoing the invention consists in the improvement hereinafter described and definitely claimed.

In the drawings:

Figure 1 is a top plan view of a ratchet wrench in accordance with this invention.

Figure 2 is a similar view with parts broken away and parts in section.

Figure 3 is a side elevation thereof with parts broken away.

The lever or handle 1 of the improvement is provided at one of its ends with the usual spaced plates that form the said end of the lever with a bifurcated head 2. The head plates are held in spaced relation by bolts or like elements 3 and there is received in the head the usual toothed wheel 4 formed with oppositely extending rounded portions that pass through rounded openings in the head 2, the rounded portions terminating in sockets 5 and 6, respectively. The bore of the socket 5 is preferably of hexagonal formation while the outer end of the cross sectionally rounded member 6 has its open end rounded inwardly to provide the same with a squared opening 7. Passing through the part 6 above the opening 7 there is a double headed rod 8, and whereby the socket members may be turned by hand if desired. Of course, removable sockets are designed to have their shanks received in the bores of the sockets 5 and 6 so that the wrench may be

employed for different sized nuts on the heads of bolts.

Between the members comprising the head there is pivotally mounted a substantially U-shaped dog 9 whose ends are shaped to provide the same with teeth 10, respectively. The teeth constitute the active ends of the dog. Secured to the center of the dog and journaled in bearing openings in the head 2 of the lever there is a cross sectionally rounded pivot member 11, one end of which projects through one side of the head, and this projecting end is bifurcated, as at 12. There is received in the bifurcated portion 12 of the pivot 11 one end of an angle arm 13. The pivot 14 for the angle arm is preferably removable, and secured to the inner face of the outer portion of the arm there is one end of a helical spring 15, the second end of which being secured to an ear or like element 16 on the handle or lever adjacent to the juncture of the head therewith.

By swinging the angle arm 13 on its pivot 14 to either side of the head the spring 15 will turn the pivot and likewise turn the dog 9 to bring either of its active ends or teeth 10 into engagement with the toothed wheel 4 so that a nut or like device engaged by the wrench may be turned in either or in both directions without removing the wrench therefrom. The slideable rod or handle 8 may be employed for turning the wrench without the necessity of rocking or imparting an oscillatory movement to the lever 1, but obviously the rod 8 cannot be employed for screwing a nut or bolt fully home but will materially facilitate the starting of such nut or bolt before the same is screwed entirely home.

It is believed the foregoing description when read in connection with the accompanying drawings will fully and clearly set forth the advantages of our improved device to those skilled in the art to which such invention relates so that further detailed description will not be required. Obviously we do not wish to be restricted to the specific structure herein shown and described and, therefore, hold ourselves entitled to make such changes therefrom as fairly fall within the scope of what we claim.

Having described the invention, we claim:

1. A lever having a bifurcated end providing a head, a toothed wheel having rounded portions extending therefrom and the opposite sides thereof journaled through the head and sockets projecting from said rounded portions, a substantially U-shaped dog having its ends formed with teeth arranged between the head, a pivot to which the dog is secured journaled through the head and having one of its ends bifurcated, an angle arm pivotally secured in the said bifurcation and a coiled pressure spring secured to the angle end of the arm and to the lever at its juncture with the head.
2. A lever having a bifurcated end providing a head, a toothed wheel having rounded portions extending therefrom and the opposite sides thereof journaled through the head and sockets projecting from said rounded portions, a substantially U-shaped dog having its ends formed with teeth arranged between the head, a pivot to which the dog is secured journaled through the head and having one of its ends bifurcated, an angle arm pivotally secured in the said bifurcation and a coiled pressure spring secured to the angle end of the arm and to the lever at its juncture with the head, spacer elements for the bifurcated head, and a double headed rod slidably associated with one of the sockets.

In testimony whereof we affix our signatures.

35 WILLIAM J. GREUTMAN.
CHARLES A. SHOOK.
MAX F. BRANDT.
